UNITED STATES PATENT OFFICE.

SAMUEL LEAR, OF POTTSVILLE, PENNSYLVANIA.

SASH-HOLDER.

SPECIFICATION forming part of Letters Patent No. 278,439, dated May 29, 1883.

Application filed March 6, 1883. (Model.)

To all whom it may concern:

Be it known that I, SAMUEL LEAR, a citizen of the United States, residing at Pottsville, in the county of Schuylkill and State of Pennsylvania, have invented a new and useful Improvement in Sash-Locks, of which the following is a specification.

My invention relates to improvements in devices for locking window-sashes; and my objects are to provide a means for holding the sash in any desired position, and to keep the sash from shaking or rattling. I attain these objects by use of the mechanism illustrated in the accompanying drawings, in which—

15 Figure 1 is a full view of my sash-lock as applied to a window-sash. Fig. 2 is a top view, having the top cut away to show its arrangement of parts and construction; and Fig. 3 is a front edge view, having a part cut away to 20 show the device for securing immovably the whole device.

Similar letters refer to similar parts in all the views.

To construct my device I take the plate B', 25 having the flange B³, and the lug or stop B², all combined in one piece, and secure it to the sash by means of a screw or any suitable fastening. In the case A, I adjust an elastic substance, X, as shown in Fig. 2, and then place 30 the spring S, as shown in same figure. The screw D is then inserted, as shown in Fig. 1, and the sash-lock is ready for operation. It will be seen that when the sash is raised its own weight will cause the sash-lock to press against the window-frame and hold the sash up, the elastic substance X holding firmly and yet preventing the marring or destruction of the window-frame. By pressing on the lever C the case A is moved, the screw D acting as 35 a pivot, thus releasing the sash-lock from engaging with the window-frame and allowing the sash to be either raised or lowered at will. As soon as the hand is removed from the lever 40

45 C the spring S acts and forces the case A back against the window-frame. To further insure the locking of the sash, I provide a supplemental fastening in the shape of a small bolt device, in which H is the bolt, K a bolt-hole in the plate B', L a spring to force the bolt downward, and H' a knob or handle on the 50 bolt, which turns into a small slot to hold the bolt up when not in use. When the bolt H is shot into the hole K in the plate B' the sash-lock is so fastened that it cannot be moved. This supplemental fastening I place on the 55 lower left-hand corner of the case A, as shown. It does not fasten the sash, but is intended to fasten together the case A and the base-plate B', so that the sash-lock remains firm and cannot be operated until the fastening is released. 60 The lug B² is used as a stop to prevent the device from being wedged too tightly against the window-frame.

My device may be used either with or without the supplemental fastening device.

What I claim as my invention, and desire to 65 secure by Letters Patent, is—

1. The within-described sash-lock, consisting of the stationary plate B', having flanged side B³ and lug or stop B², in combination 70 with the case A, having the lever C and elastic substance X, the spring S, held behind flange B³ and upper flange of A, and the screw D, as shown and set forth.

2. In the within-described sash-lock, the 75 combination of the case A, having lever C and elastic substance X, the plate B', having lug B² and flanged side B³, the spring S, and the screw D, with the supplemental fastening-bolt, all combined and arranged as shown and set 80 forth.

SAMUEL LEAR.
